DESIGN FOR A COMBINED DIAL AND HANDS FOR A CLOCK OR SIMILAR ARTICLE

Louis Moro, Danbury, Conn.

Application April 8, 1936, Serial No. 62,020

Term of patent 14 years

To all whom it may concern:

Be it known that I, Louis Moro, a citizen of the United States of America, residing at Danbury, in the county of Fairfield and State of Connecticut, have invented a new, original, and ornamental Design for a Combined Dial and Hands for a Clock or Similar Article, of which the following is a specification, reference being had to the accompanying drawing, forming a part thereof.

Figure 1 is a view in elevation of a combined

dial and hands for a clock or similar article showing my new design.

Figure 2 is an edge view.

The printed matter both as to the formation of the letters of the alphabet and the arrangement on the dial and the hands, appearing on Figure 1, are merely illustrative.

I claim:

The ornamental design for a combined dial and hands for a clock or similar article, as shown.

LOUIS MORO.
